UNITED STATES PATENT OFFICE.

RICHARD C. LEAKE, OF ROCHESTER, NEW YORK, ASSIGNOR TO GENERAL RAILWAY SIGNAL COMPANY, OF ROCHESTER, NEW YORK, A CORPORATION OF NEW YORK.

STARTING SWITCH FOR SINGLE-PHASE MOTORS.

Application filed August 17, 1920. Serial No. 404,233.

This invention relates to centrifugal switches, and more particularly to a switch for starting single phase induction motors.

The principal objects of my invention are 5 to devise a speed responsive switch of the centrifugal type which will act positively and quickly to make and break the desired circuit connections at predetermined speeds, which comprises few and simple parts easily 10 and cheaply manufactured and assembled, and which possesses the various other features of construction and operation desirable in switches of this character. Various specific features and advantages will appear 15 hereinafter as the description progresses.

In describing the invention in detail reference will be made to the accompanying drawings in which

Figure 1 is a longitudinal diametrical section through a single phase motor of the usual type, with my improved starting switch applied thereto;

Fig. 2 is a section taken substantially on the line 2—2 in Fig. 1 and shows an end 20 view of the rotor;

Fig. 3 is a transverse section through the motor switch taken substantially on the line 3—3 in Fig. 1;

Figs. 4 and 5 are sections taken substantially on the lines 4—4 and 5—5 respectively in Fig. 1 and looking in the direction indicated by the arrows;

Fig. 6 is a fragmentary section on the line 6—6 in Fig. 5; and

Fig. 7 illustrates the rotor and switch diagrammatically in perspective, with some parts broken away and spread apart, together with the circuit connections preferably employed.

Referring to the accompanying drawings, I have shown my improved starting switch applied to a single phase motor of the usual construction comprising a frame F, a laminated stator S with coils or windings W constituting the usual starting and running field windings for the stator, and the rotor R fixed to a shaft 1. This shaft 1 is journaled in bearings supported by end caps C and C¹, provided with openings for ventilation 45 in the usual way. The upper part of the end cap C is covered by a cover or shield D having therein an insulating bushing 2 for receiving the lead or power wires for the motor.

Secured to the inside face of the cap C by

screws 3 (see Fig. 5) is a panel P of suitable insulating material, to which are fastened two binding posts 4 for facilitating the inter-connection of wires. The panel P is formed with a number of raised portions, preferably three in number and spaced equally around the shaft, and to each of these raised portions is fastened, by rivets or the like, a contact piece 5, of German silver, phosphor bronze, or similar material.

Cooperating with the three contact pieces 5 is a contact ring 6, preferably made of phosphor bronze, steel, or a similar comparatively hard conducting material. I prefer in most cases to make the contact ring 6 of a

harder material than the contact pieces 5. The ring 6 is fastened by rivets or the like to a disc 7 of insulating material which fits loosely on a sleeve 8 surrounding the shaft 1.

The disc 7 is urged outward toward the fixed contacts 5 by a spring 9; and its outward movement is limited by a collar 10 fixed to the sleeve 8. The sleeve 8 itself is spring-pressed outward by a spring 11 around the shaft 1, and to economize in space, this

spring is partly enclosed within a recess in said sleeve. Fastened to the inner end of sleeve 8 by rivets or the like, is an irregular shaped member or plate 12. This plate 12 is formed with notches 13 in its outer edge (see Fig. 3), three of these notches being preferably employed. A member 14 fastened by screws 15 to the end of a rotor R is formed with arms 16 projected parallel

with the shaft 1 and engaging the notches 13, so that the sleeve 8 turns with the rotor and its shaft but may slide longitudinally.

The centrifugal elements of the switch comprise a plurality of bars 17 which extend through the holes in the rotor R, such holes being commonly employed for the purpose of ventilation. In the specific embodiment illustrated, there are three of these bars 17 arranged at equal intervals around the shaft 1. One end of each bar 17 passes loosely through a slot in the plate 12, and is prevented from pulling out of this slot by a washer and small transverse pin. The other end of each bar 17 is pivotally connected to the lower end of a pair of links 18 (see

Figs. 1 and 2). These pairs of links 18 project outwardly from the shaft 1 at an angle, and are pivotally supported at their upper ends between a pair of ears 19 punched out of a plate 20 fastened by screws 21 to

105
110

the end of the rotor R. The plate 20 also has fan blades 22 stamped out of it.

Operation.—When the rotor is at rest the parts assume the position shown in Fig. 1, the sleeve 8 being pressed out by the spring 11, and the contact ring 6 being pressed into contact with the fixed contact pieces 5 by the spring 9.

The fixed contact pieces 5 bear against the ring 6 at three points, thereby assuring intimate contact between said ring and each contact piece. When the motor is started and the shaft 1 revolves, the disc 7 and the contact ring 6 is held stationary by a drag upon the fixed contact pieces 5, said disc 7 slipping around the sleeve 8. As the speed of the shaft 1 increases, the bars 17 tend to move outward by centrifugal force, and at a predetermined critical speed, these bars are thrown outward, thereby rocking the links 18, and pulling the sleeve 8 inward against the opposition of the spring 11. As the sleeve 8 moves inward, the tension of the spring 9 is relaxed, and finally the contact ring 6 is pulled away from the fixed contact pieces 5, thereby breaking the circuit through the starting winding. As soon as the contact ring 6 leaves engagement with the fixed contact pieces 5, it accelerates, and all of the parts revolve together with the shaft 1, without any engagement or rubbing.

When the speed of the motor falls below the critical speed, the spring 11 overcomes a centrifugal force exerted by the bars 17, and acts to return the parts to the position shown, and again cut in the starting winding.

Referring to Fig. 7, 23 designates the running winding and 24 the starting winding. When the switch 25 is closed, the running winding 23 is connected directly across the supply mains 26, and the starting winding 24 is connected in multiple therewith through the contact pieces 5 and the contact disc 6, two of the contacts 5 being preferably connected in multiple.

One important feature of my improved switch is the quick break. It will be noted that when the bars 17 move outward from the normal position shown in Fig. 1, the moment of centrifugal force about the fixed pivotal connection of the upper end of the pairs of links 18 increases, while the moment about this same point produced by the spring 11 decreases. Also, as these bars move outward, their radius of gyration increases, so that the centrifugal force exerted by these bars increases independently of the angular velocity as said bars move outward. Thus, when the centrifugal force of the bars 17 in their inner or normal position once overcomes the tension of the spring 11, and the bars 17 start to move out, they fly out quickly, because they acquire an increased

mechanical advantage over the spring 11 as they move out, and also acquire an increased speed, and consequently, an increasing centrifugal force. This results in a quick snap movement of the contact ring 6, and serves to prevent burning or injuring of the contacts by long drawn out arcs. Furthermore, as the pressure of the contact ring 6 upon the fixed contact pieces 5 is relaxed, said ring commences to rotate, so that any arc that may be drawn is spread over a comparatively wide surface and there is no opportunity for local heating and pitting. When the motor slows down, and the contact ring 6 engages the contact pieces 5, said ring rubs over said pieces to some extent, so as to clean the surfaces and rub down whatever minute projections of metal may have been drawn up by arcing during the preceding opening of the switch, with the result that said contact ring and contact pieces maintain a serviceable surface after many operations. The critical speed at which the switch will open depends upon the tension of the spring 11, the weight of the bars 17, and the proportioning and arrangement of parts in general; and by varying these factors, a switch may be constructed in accordance with my invention which will open at any desired critical speed and close at some lower critical speed.

The specific construction shown and described is merely illustrative of my invention and is susceptible of adaptation and modification in practice.

What I claim as new and desire to secure by Letters Patent of the United States, is:

1. In an electric motor of the type which includes a shaft and a rotor thereon having holes extending therethrough parallel with the shaft, a centrifugal switch comprising, a plurality of stationary, insulated contacts arranged around said rotor shaft, a sleeve mounted on said shaft and movable axially thereon, a spring acting to move said sleeve axially towards said contacts, and an insulated contact ring carried by the sleeve for engaging and electrically connecting said contacts, weighted bars connected at one end to said sleeve and extending lengthwise of the rotor shaft through the holes in said rotor, and links pivotally connected at one end to the rotor and at the other end to the corresponding weighted bar, said links extending from their pivotal connection to the rotor outwardly, therefrom and toward the rotor shaft, said bars being movable outward radially with respect to the rotor shaft about the ends connected to the sleeve and being moved, lengthwise by said links as the bars move outwardly.

2. In an electric motor of the type which includes a shaft and a rotor thereon having holes extending therethrough parallel with the shaft, a centrifugal switch comprising a

- sleeve mounted on the rotor shaft and movable axially thereon, a spring acting to move said sleeve in one direction, circuit controlling means actuated by the axial movement 5 of the sleeve, a plurality of weighted bars extending through said holes in the rotor and operatively connected at one end to said sleeve, a link pivotally connected at one of its ends to the other end of each bar and 10 at the other of its ends to the rotor, said links being inclined with respect to the axis of the rotor shaft with their ends connected to the rotor farther from the shaft than their other ends connected to said bars, 15 whereby the axial pull of the bars on the sleeve increases as the bars move outwardly.
3. In an electric motor of the type which includes a shaft and a rotor thereon having holes extending therethrough parallel with 20 the shaft, a centrifugal switch comprising, a plurality of contacts disposed around the rotor shaft, a sleeve mounted on the rotor shaft and movable axially thereon, a spring acting to move said sleeve toward the contacts, a contact disk rotatable on the sleeve, a spring on the sleeve acting on the disk to move it against said contacts, a plurality of weighted bars each connected at one end to said sleeve and extending lengthwise of 25 the shaft through said holes in the rotor with their opposite ends closer to the shaft, and a link pivotally connected at one end to said opposite end of each of said bars and also pivotally connected at its other 30 end to said rotor, said links being inclined to form with their corresponding bars an acute angle which decreases as the bars are moved outwardly by centrifugal force.
4. In an electric motor of the type which 35 includes a shaft and a rotor thereon having
- holes extending therethrough parallel with the shaft, a centrifugal switch comprising, three stationary insulated contacts arranged around the rotor shaft, a sleeve movable axially on the shaft, an insulated contact link 45 ring rotatably mounted on the sleeve and co-operating with said contacts, a spring acting to move the sleeve axially in one direction, three bars pivoted at one end to the sleeve and extending lengthwise of the rotor shaft through said holes in the rotor, and inclined links each pivotally connected at one end to the rotor and at the other end to one of said bars, said bars when moved radially outward from the shaft by centrifugal force being shifted lengthwise by said 50 links and acting to pull said sleeve and separate the contact ring from the stationary contacts.
5. In an electric motor of the type which includes a shaft and a rotor thereon having holes extending therethrough parallel with the shaft, a centrifugal starting switch comprising, a circuit controlling element movable axially on the rotor shaft, a spring 60 pressing said sleeve in one direction, a plurality of relatively long bars extending lengthwise of the rotor shaft through the holes in the rotor and connected at one end to said element, and inclined links each piv- 65 otally connected at one end to the rotor and at the other end to the outer free end of the corresponding bar, each bar and its link normally forming an acute angle which decrease as the bars move outward by centrif- 70 ugal force.
- In testimony whereof I have affixed my signature.

RICHARD C. LEAKE.
